MACHINE FOR PACKAGING FLUENT MATERIAL

Charles C. Smith, Peoria, Ill.

Application August 5, 1954, Serial No. 448,037

10 Claims. (Cl. 53—281)

This invention relates to an improved machine for 15 packaging ice cream or other fluent material.

One principal object of the invention is to provide a machine for packing ice cream or the like into cardboard packaging tubes or similar containers suitable for dispensing by means of vending machines.

A further object is to provide a packaging machine of the foregoing character which will operate automatically, with only occasional replenishment of the supply of packaging tubes and caps.

It is another object of the invention to provide a packaging machine having means for automatically feeding packaging tubes into a conveyor adapted to carry the tubes to successive stations at which the tubes will be filled and closed.

A further object of the invention is to provide a packaging machine of the foregoing character having improved means for capping the lower ends of the tubes, filling the tubes with ice cream or other fluent material, and closing the upper ends of the tubes.

Another object is to provide a packaging machine having improved means for preventing spillage of the fluent material in the event that the feeding mechanism fails to feed a tube to the conveyor or the bottom capping mechanism fails to close the lower end of a packaging tube.

It is a further object of the invention to provide a packaging machine arranged to prevent breakage of any part of the machine in the event that a packaging tube or a cap becomes jammed in the machine.

Further objects and advantages of the invention will appear from the following description, taken with the accompanying drawings, in which:

Figure 1 is a perspective view showing the front of an ice cream packaging machine constituting an illustrative embodiment of the invention.

Fig. 2 is an exploded perspective view of a container adapted to be filled with ice cream or the like by the machine of Fig. 1.

Fig. 3 is a perspective view taken from the right side of the machine of Fig. 1.

Fig. 4 is a fragmentary enlarged perspective view taken from the right side of the machine.

Fig. 5 is a fragmentary enlarged perspective view taken from the left side of the machine.

Fig. 6 is an enlarged fragmentary perspective view taken from the left front of the machine.

Fig. 25 is a fragmentary elevational sectional view taken generally along a line 25—25 in Fig. 23.

Fig. 26 is a continuation of the lower portion of 40 Fig. 25.

Fig. 27 is a fragmentary elevational view, partly in section, along a line 27—27 in Fig. 24, to show a mechanism for stopping the machine in the event that a tube is missing in the conveyor.

Fig. 28 is a fragmentary elevational sectional view 45 taken generally along a line 28—28 in Fig. 9, to show details of the filling mechanism embodied in the machine.

Fig. 29 is an elevational sectional view taken generally along a line 29—29 in Fig. 9.

Fig. 30 is a fragmentary horizontal sectional view taken generally along a line 30—30 in Fig. 29.

Fig. 31 is a fragmentary horizontal sectional view taken generally along a line 31—31 in Fig. 29.

Considered in greater detail, Fig. 1 illustrates a packaging machine 40 adapted to pack ice cream or other fluent material into containers 41 of the type shown in Fig. 2. The illustrated container comprises a waxed cardboard cylindrical packaging tube 42 which may be perforated or scored at its midpoint, as indicated at 43, so that the tube may readily be broken in half when the ice cream in the tube is to be consumed. Disc-shaped cardboard caps 44 are employed to close the upper and

lower ends of the tube 42. As indicated, the caps are adapted to be inserted into the open ends of the tube.

Initially, a brief overall description of the packaging machine 40 will be undertaken. The machine 40 is built on a frame or table 46 which supports the various components. To provide a supply of the packaging tubes 42, a magazine or hopper 47 is mounted on the front end of the table 46, the tubes being held in horizontal position in the hopper. A feeding mechanism 48 is provided to feed the tubes from the hopper 47 into a conveyor 49, the feeding mechanism being operative to erect the container tubes from a horizontal to a vertical position.

In this instance, the conveyor 49 comprises a wheel or rotatable nest 51 having a plurality of angularly-spaced, generally semi-cylindrical recesses or pockets 52 adapted to receive the container tubes 42. An arcuate guide or fence 53 is provided to retain the tubes 42 in the pockets 52.

The conveyor nest 51 is mounted on a vertical shaft 55 adapted to be rotated intermittently so as to carry the container tubes 42 to a series of stations. As indicated in Fig. 9, the tubes 42 are fed into the conveyor nest at a station 56. The conveyor 49 carries the tubes to a station 57 at which a safety switch mechanism 58 (Figs. 6 and 27) makes a test to determine whether a tube is present in the conveyor. If a tube is missing, the switching mechanism 58 stops the operation of the machine so that a tube may be inserted manually. This arrangement prevents spillage of ice cream into an empty conveyor pocket.

From the testing station 57, the tubes 42 are advanced to a station 60 provided with a mechanism 61 for inserting one of the caps 44 into the lower end of each tube 42. At a succeeding station 62, a testing mechanism 63 is provided to determine whether a cap is present in the tubes 42 as they arrive at the station. If a cap is missing, the mechanism 63 stops the machine to prevent spillage of ice cream.

The container tubes 42 are filled with ice cream or other fluent material by means of a filling mechanism 65 at a succeeding station 66. Caps 44 are inserted into the tops of the tubes at a station 67 by means of a top capping mechanism 68. Finally, the filled containers 41 are removed from the conveyor nest 51 at a station 70. This is done by means of a pair of vertically-spaced, curved stripper fingers 71 and 72 interposed in the path of the advancing containers and arranged to cam the containers outwardly from the pockets 52. The containers pass by gravity onto an apron 73 from which they may be packed into cartons for shipment.

To rotate the conveyor nest 51, the packaging machine is equipped with an advancing mechanism 75 (Figs. 10-13) which includes a ratchet wheel 76 mounted on the lower end of the conveyor shaft 55. The ratchet wheel 76 is engaged by a pawl 77 pivotally mounted on an arm 78. An elongated sleeve 79 is rotatably received over the shaft 55 to support the arm 78. The arm 78 is oscillated by means of a cam 80 mounted on a cam shaft 81 which is continuously driven by a suitable motor (not shown). The cam 80 acts on a follower roller 82 mounted on a lever 83 which is connected to the arm 78 by means of a link 84. A spring 85 is provided to bias the lever 83 in one direction and thereby maintain the roller 82 in engagement with the cam 80. The arrangement of the advancing mechanism 75 is such that the ratchet wheel 76 is advanced by the spring 85 on the descending portion of the cam 80. The effect of the cam is to return the pawl 77 positively for each successive advancing stroke. With this arrangement, the machine will not be damaged if a faulty container or some other object becomes jammed in the conveyor nest 51.

Any stoppage of the rotation of the nest 51 simply holds the cam follower roller 82 away from the cam 80

so that the cam can continue to rotate in its normal manner.

To prevent the conveyor nest from being overthrown beyond the normal advancing interval by the ratchet-advancing mechanism 75, a friction brake 87 is connected to the conveyor. The illustrated brake 87 comprises a pair of arcuate brake bands 88 spring-biased against a drum 89 which is mounted on the conveyor shaft 55.

As shown in Figs. 14 and 15, a registering mechanism 91 is provided to position the conveyor nest 51 accurately after each advancing step so that the tubes 42 will be accurately registered with the various capping and filling components of the machine. The illustrated registering mechanism 91 comprises a locking pin or detent 92 adapted to enter a series of apertures or recesses 93 formed in a member carried by the conveyor nest 51. In this instance, the recesses 93 are formed in the inner portion of the ratchet wheel 76. A cam 95 is provided to advance the locking pin 92 into each successive aperture 93 after the ratchet wheel 76 has been advanced by the pawl 77. The cam acts upon a cam follower roller 96 mounted on a lever 97 which supports the locking pin 92. A spring 98 is employed to bias the lever 97 in one direction so as to hold the roller 96 against the cam. The arrangement of the mechanism is such that the pin 92 is advanced into the apertures 93 by the spring 98 and is positively withdrawn by the cam 95. This arrangement avoids damage to the machine in the event that the locking pin 92 cannot enter the apertures 93 due to faulty operation of the advancing mechanism 75.

The hopper 47 (Fig. 1) for holding a supply of the container tubes 42 is of generally rectangular box-like form and is provided with an open top and an open front for loading the tubes into the hopper. The entire hopper is slightly tilted rearwardly to retain the tubes 42. As illustrated, the hopper 47 comprises opposite side walls 102 and 103, a rear wall 104, and a bottom wall 105 which slopes downwardly toward the left side of the hopper. At its lefthand end, the bottom wall 105 forms one element of a ramp 106 adapted to carry the tubes 42 into the feeding mechanism 48. A baffle plate 107 extending parallel to the left-hand portion of the lower wall 105 forms the upper element of the ramp 106, the spacing between the walls 105 and 107 being such as to admit the tubes in single file. An upwardly-sloping plate 108 extends to the left from the right-hand end of the plate 107 so as to direct the tubes 42 into the entrance of the ramp 106, the entrance being defined by the right-hand end of the plate 107.

To insure that the containers 42 will move uninterruptedly into the ramp 106, the hopper 47 is provided with an agitator which takes the form of a generally horizontal plate 110 mounted on a horizontal pivot 111 adjacent the right-hand end of the lower wall 105. The agitator plate 110 is swung between the full and dotted line portions shown in Fig. 17b by means of a link 112 (Fig. 17b) formed with a lost motion slot 112a. The slot 112a receives a pin 112b mounted on a lever 112c, which is connected to a rock shaft 113 by linkage 113a. A lever 114, operated by a suitable cam (not shown), is provided to oscillate the shaft 113. An arcuate depending guide 115 is mounted on the left-hand end of the agitator plate 110 to exclude the tubes 42 from the space between the agitator and the lower wall 105.

At its uppermost position, the left-hand end of the agitator plate 110 is opposite the right-hand end of a plate 117 having its opposite end mounted on a pivot or hinge 118 connected to the left-hand hopper wall 102. The plate 117 slopes downwardly from the pivot 118, but is free to swing upwardly about the pivot as the tubes are agitated by the swinging movement of the plate 110. It will be seen that the outer ends of the plates 110 and 117 define a gate between which the containers pass in moving from the hopper 47 into the ramp 106. A member 119 extends upwardly between the plates 108

and 117 to restrict upward movement of the tubes beneath the plate 117.

At its lower end, the ramp 106 communicates with a vertical chamber 125 (Fig. 17) in which the packaging tubes 42 are erected from a horizontal to a vertical position. A lever 126 controls the movement of the tubes 42 from the ramp 106 to the erecting chamber. The lever 126 is formed with a pair of arms 128 and 130 and is mounted on a pivot 132 as shown in Fig. 17a, the arm 130 including a pair of chisel-pointed end portions 133. The weight of the arm 130 biases the lever in such a direction that the arm 128 is normally positioned in the path of the tubes 42 at the entrance to the chamber 125. However, the lever 126 is cyclically swung, in a manner to be described shortly, to a position such that the arm 128 is withdrawn from the path of the tubes. Movement of the lever 126 to this position swings the arm 130 upwardly between two of the tubes 42 in the ramp, with the result that the arm 130 pushes the foremost tube into the erecting chamber 125. In this way, the packaging tubes 42 are introduced one at a time into the erecting chamber 125.

It will be seen from Figs. 1 and 6 that the erecting chamber is formed by a skeletal bottom wall 136 and a pair of upright side walls or guide plates 138 and 140 which extend rearwardly into spaced relation to the conveyor nest 51. As shown in Fig. 6, the stripper fingers 71 and 72 are formed on the left-hand guide plate 138.

A lever 142 is provided in the erecting chamber 125 to erect the container tubes 42. As shown in Fig. 16, the lever 142 is mounted on the shaft 113 for swinging movement between generally horizontal and generally vertical positions, represented by full and dotted lines, respectively, in Fig. 16. In its horizontal position, the lever 142 is received in a recess 146 formed in the bottom wall 136 so that the packaging tubes 42 can roll onto the lever in entering the erecting chamber 125. When the lever 142 moves to its vertical position, the packaging tube 42 is swung between the guide plates 138 and 140 into an upright position, and is advanced into one of the pockets 52 in the conveyor nest 51. It will be understood that tubes 42 are fed into the nest 51 during the dwell periods of the conveyor.

In the illustrated construction, the feed lever 126 is provided with an operating arm 150 (Fig. 17) which extends laterally into the path of the erecting lever 142. When the lever 142 moves downwardly toward its horizontal position, it engages the arm 150 and thereby actuates the lever 126 so that the next packaging tube 42 will be pushed into the erecting chamber 125. On the upstroke of the erecting lever 142, the actuating arm 150 swings upwardly into the lower portion of the erecting chamber. Accordingly, the tubes 42 move down the ramp 106 until they are arrested by the arm 128.

It will be recalled that the container tubes 42 are introduced into the conveyor nest 51 at the station 56 and then are carried to the station 57, where a testing device 58 is provided to determine whether there is a tube in the nest at this point. The illustrated testing device 58 (Figs. 6, 24 and 27) comprises a vertically movable member 154 which is engageable with the upper end of the tube 42 at the station 57. In this instance, the member 154 takes the form of a plate mounted on the lower end of a pair of guide rods 155 and 156 which are slideable vertically in a horizontal support 158. A spring 159 is provided to bias the plate 154 downwardly relative to the support 158. Downward movement of the plate is limited by a stop collar 160 on the guide rod 155.

The plate 154 is moved into engagement with the tube 42 at the station 57 by means of a vertically reciprocable bar or other support 162, which carries the member 158. It will be seen from the ensuing description that this bar 162 also performs a number of other functions. The bar 162 is mounted between the upper ends of a pair of vertically slideable rods 163 and 164 which are connected

together at their lower ends by a member 165 (Fig. 26). A lever 166 is employed to reciprocate the member 165 vertically. The lever 166 carries a roller 168 which engages a suitable actuating cam 169 mounted on the cam shaft 81.

By virtue of the reciprocation of the bar 162, the plate 154 is moved downwardly over the station 57 during each dwell period of the conveyor. If a packaging tube 42 is present in the conveyor pocket 52 at the station 57, the plate 154 is arrested in its downward movement with the result that the support 158 moves downwardly along the guide rods 155 and 156 against the biasing action of the spring 159. If the conveyor pocket 52 is empty, the plate 154 moves downwardly into engagement with an operating plunger 171 of a switch 172 or other control element capable of stopping the operation of the machine. A packaging tube 42 may then be inserted manually into the conveyor pocket so that ice cream will not be spilled when the pocket reaches the filling station 66. It will be understood that the upper end of the plunger is below the level of the top of the packaging tube 42 so that the switch 172 is not operated when a packaging tube is present in the conveyor nest 51 at the testing station 57.

As already indicated, one of the disc-shaped caps 44 is inserted into the lower end of each of the packaging tubes 42. A supply of the caps 44 is maintained at the capping station 60 in a tubular magazine 174 provided with a longitudinal slot 175 to facilitate insertion and removal of the caps to and from the magazine. The magazine tube 174 is adapted to be received in a similarly slotted mounting sleeve 176 having its lower end fixed in an opening 178 formed in a supporting plate 179. A pivot 180 is provided to support the plate 179 for swinging movement in a horizontal plate. In this way the plate 179 and the magazine 174 may be swung out of the way to facilitate cleaning of the machine and removal of any jammed caps from the under side of the plate. A clamping screw 181 is provided to hold the plate 179 in its operative position.

To remove the caps 44 one at a time from the magazine 174, a slicer blade or plate 182 is mounted on an actuating shaft 184 for horizontal swinging movement underneath the magazine-supporting plate 179. The slicer blade 182 is formed with an arcuate leading edge 185 adapted to slice the lowermost cap 44 in the magazine 174 and advance the cap laterally to the capping station 60. A trailing tail portion 186 is provided on the slicer blade 182 to support the remaining caps in the magazine 174 until the blade is returned to its fully retracted position (Fig. 22). To operate the slicer blade 182, an arm 188 (Figs. 10 and 11) is mounted on the slicer shaft 184 for engagement with a roller 189 on an arm 190 carried by the oscillating sleeve 79 of the conveyor-advancing mechanism 75. The oscillations of the sleeve 79 are effective to return the slicer blade 182 to its retracted position. A spring 192 is connected to the shaft 184 in order to advance the slicer blade 182. With this arrangement, the machine will not be broken in the event that one of the caps 44 jams in the machine and prevents the advance of the slicer blade 182. If such jamming occurs, the arm 188 will simply be prevented from following the roller 189 under the impetus of the spring 192.

The table 46 is provided with a top plate or other horizontally disposed member 194 to support the lower ends of the packaging tubes 42. At the capping station 60 (Fig. 21), a die plate 194a is set into the plate 194. A recess 195 is formed in the plate 194a to receive the lower end of the packaging tube 42 at the station 60 so as to accurately position the packaging tube and form the lower end of the tube into a round shape, preparatory to the insertion of a cap. The packaging tubes 42 are pushed downwardly into the recess 195 by means of a plunger 197 which in this instance is mounted on the

vertical reciprocable bar 162. Shortly after the packaging tube 42 arrives at the station 60, the plunger 197 descends and the reduced portion 198 on its lower end enters the upper end of the tube 42. This has the effect of rounding out the tube in preparation for the subsequent top capping operation. A tapered portion 199 is formed on the lower end of the reduced portion 198 to facilitate entry of the plunger 197 into the tube 42. At the upper end of the reduced portion 198, a shoulder 200 is provided on the plunger 197 to engage the upper end of the tube 42 and thereby push the tube downwardly into the recess 195. The plunger 197 remains in engagement with the upper end of the tube 42 during the bottom capping operation so as to prevent the tube from moving upwardly.

To drive the cap 44 into the lower end of the tube 42 at the capping station 60, a plunger 202 (Figs. 18a, 20 and 21) is positioned for vertical reciprocation in a bore 203 formed in the plate 194 beneath the recess 195. It will be understood that the slicer blade 182 is operative to advance the caps 44 into a space 204 immediately above and in vertical alignment with the plunger 202. The plunger 202 is reciprocated by means of a lever 206 carrying a roller 207 which is engageable with a cam 208 mounted on the cam shaft 81. A spring 209 is provided to swing the lever in such a direction as to raise the plunger 202, the roller 207 meanwhile following the cam 208. The plunger 202 is retracted positively by the operation of the cam 208. The spring 209 thus supplies the force for driving the caps 44 into the packaging tubes. If the plunger 202 should be prevented from advancing by a jammed cap, the roller 207 will be prevented from following the cam 208, but no damage to the machine will result. After the cap 44 has been driven into the tube 42, the capping plunger 202 dwells momentarily while the hold down plunger 197 moves upwardly to release the tube 42 for upward movement. Next, the capping plunger 202 again moves upwardly to push the tube 42 out of the forming recess 195. The tube 42 then is advanced by the conveyor nest 51.

It will be recalled that a testing device 63 is provided at the testing station 62 to determine whether a cap 44 is present in the tube 42. In the illustrated construction, the testing device 63 includes a plunger 211 movable along a vertical bore 212 in the plate 194. To provide for reciprocation of the plunger 211, it is connected to a lever 214. In order that the plunger 211 may be arrested by the cap 44 in the tube 42 at the testing station 62, the lost motion connecting device 215 is interposed between the lever 214 and the operating lever 206 for the capping plunger 202. In this instance the lost motion connection 215 comprises a rod 216 movable through an apertured bracket 218 on the lever 206. The rod 216 is pivotally connected to the lever 214 and is provided with upper and lower stop collars 219 and 220 to limit the range of relative movement between the levers 206 and 214. A spring 221 is interposed between the bracket 218 and the lower stop collar 220 to move the plunger 211 upwardly in unison with the capping plunger 202. If a cap 44 is present in the tube 42 at the testing station 62, the cap arrests the plunger 211 in its upward movement. Further movement of the actuating lever 206 merely compresses the spring 221. On the other hand, if the tube 42 is without a bottom cap, the plunger 211 moves upwardly through the full range of movement of the lever 206 with the result that the lever 214 depresses a plunger 224 on a control switch 225 which is effective to stop the machine. In this way, the testing device 63 prevents any tube without a bottom cap from being advanced to the filling station 66. An arm 226 prevents upward movement of the tubes 42 at the testing station 62.

At the filling station 66, ice cream or other fluent material is extruded into the packaging tubes 42 through outer and inner filling nozzles 230 and 231 arranged con-

centrically as shown in Fig. 8. Different materials may be extruded through the two nozzles 230 and 231 in order to form a core in the body of ice cream in each of the tubes 42. The most common practice is to extrude a flavored syrup through the inner nozzle 231 while extruding ice cream through the outer nozzle 230.

The illustrated filling mechanism 65 comprises a hopper or other reservoir 233 having two compartments 234 and 235 for the different materials to be extruded through the outer and inner nozzles 230 and 231. The compartments 234 and 235 may be regarded as the ice cream and syrup compartments respectively. Measuring cylinders 236 and 237 (Fig. 7) are provided for the ice cream and the syrup. Pistons 238 and 239 are arranged for reciprocation in the cylinders 236 and 237 in order to suck ice cream and syrup from the hopper compartments 234 and 235, and then push charges of the ice cream and syrup outwardly through the nozzles 230 and 231. The pistons may be reciprocated by a lever 241 having a variable length arm 242 connected to a link 244 which may be reciprocated by a suitable cam (not shown). The quantity of material extruded through the nozzles 230 and 231 may be varied by adjusting the length of the arm 242.

25 A rotary valve 246 provides passages between the hopper compartments 234 and 235 and the cylinders 236 and 237 when the latter are filling. A suitable cam-operated linkage 248 is provided to shift the position of the valve so that it will provide passages between the cylinders 236 and 237 and the nozzles 230 and 231 when the fluent materials are being extruded.

30 Provision is made for moving the tubular cartons 42 and the filling nozzle 239 into telescopic relation while the ice cream or other fluent material is being extruded into the tubes. In the illustrated machine, the tubes 42 are raised and slipped over the nozzle 239 preparatory to the filling operation. This is accomplished by means of a vertically reciprocable member in the form of a rod 260 positioned adjacent the filling station 66. A bushing 261 is mounted in the top plate 194 to receive the rod 260. The rod 260 is reciprocated by a cam 262 connected to the rod by means of a link 264 and a lever 265. A spring 266 is provided to bias the lever upwardly so that a roller 268 on the lever will be held against the cam 262. It will be evident that the rod 260 is moved upwardly by the spring 266 and is returned downwardly by the cam 262. If a jammed container tube 42 prevents the upward movement of the rod 260, the roller 268 will be held away from the cam 262, but there will be no damage to the machine.

35 In order to engage the lower end of the packaging tube 42 at the filling station 66, the rod 260 is equipped with an arm 269 having an inner end portion 270 extending laterally from the rod 260, together with a depending L-shaped outer portion 271 having a generally horizontal finger 272 movable into a recess 273 formed in the plate 194. It will be seen that the recess 273 extends under the packaging tube 42 positioned at the filling station 66. Thus the finger 272 is adapted to move upwardly into engagement with one edge of the tube 42.

40 During each dwell period of the conveyor nest 51, the packaging tube 42 is raised by the finger 272. The finger 272 is raised out of the recess 273 by upward movement of the rod 260 and the tube 42 is thereby telescoped over the lower end of the nozzle 239. After the tube 42 has been raised, the valve 246 operates so as to start the flow of the fluent materials from the nozzles 230 and 231 into the tube 42. Since the lower part of the tube is the first to be filled, the formation of air pockets in the tube is positively prevented.

45 As the filling operation progresses, the packaging tube 42 is removed downwardly off the nozzle 239 by a stripper element in the form of a plate 276 operable by the vertically reciprocable rod 260. In this instance, the stripper plate 276 is mounted on the upper end of the

rod 260. It will be seen that the stripper plate 276 is formed with an opening 278 received over the filling nozzle 230 for engagement with the top of the packaging tube 42. The vertical spacing between the tube-raising finger 272 and the stripper plate 276 is made substantially greater than the length of the tubes 42 to provide lost motion between the tubes and the elements 272 and 276. After being raised by the finger 272, the tube 42 remains in its raised position until this lost motion has been taken up by the downward movement of the stripper plate 276. As the lost motion is being taken up, the finger 272 moves away from the lower end of the tube 42.

To prevent the tube 42 from falling off the nozzle 230 of its own weight, a swingable gate 280 is provided in the rail 53 at the filling station 66. In order to press the tube 42 against the conveyor nest 51, the gate 280 is biased inwardly by means of a spring 281 which acts against an intermediate point on a lever 282. One end of the lever engages the gate 280 while the opposite end rests against an abutment 284. The spring 281 reacts against a thumb screw 285 which may be adjusted to vary the strength of the spring. It will be seen that a notch 286 is formed in the gate 280 to admit the finger 272.

The tube 42 is halted in its downward movement off the nozzle 230 with the upper end of the tube even with the lower end of the nozzle. The conveyor nest 51 is then indexed, with the result that the tube 42 shears off the fluent material level with the lower end of the nozzle 230. In order to hold the tube 42 in this raised position, a flipper blade 290 is provided adjacent the filling station 66. The blade 290 is horizontally disposed on a pivot 291 journaled in the top plate 194 and is thereby supported at an elevation above the top plate such as to hold the tube 42 with its upper end even with the lower end of the nozzle 230. When the conveyor nest 51 indexes each of the supporting tubes 42 to the filling station 66, one edge of the flipper blade 290 is engaged by the tube 42 and the flipper blade is thereby swung about the pivot 291 against the biasing action of a spring 292, which is connected to an arm 294 mounted on the pivot below the plate 194. When the tube 42 is raised by the finger 272, the spring 292 returns the flipper blade 290 until the arm 294 engages an adjustable stop 295. In this way the flipper blade 290 is moved into the path of the tube 142, with the result that the lower end of the tube comes to rest on the blade 290 when the tube is pushed downwardly off the nozzle 230 by the stripper plate 276. As the tube 42 is indexed away from the filling station 66, the lower end of the tube slides along the top of the blade 290. The next tube being indexed to the filling station 66 deflects the flipper blade 290 without interfering with the tube carried on the upper surface of the blade. Further indexing of the nest 51 moves the tube 42 beyond the flipper blade 290. As a result, it tends to fall against the top plate 194. If the tube 42 remains in an elevated position, it is pushed downwardly as it approaches the top capping station 67 by a paddle 298 carried by the vertically reciprocating bar 162.

The capping mechanism 68 at the top capping station 67 is similar to the capping mechanism 61 at the station 60 and hence need not be described in great detail. When each of the packaging tubes 42 reaches the top capping station 67, it is pushed upwardly into the recess 300 formed in a plate 301. Such movement of the tube 42 is effected by a vertically reciprocable plunger 302 which is engageable with the lower end of the tube. The plunger 302 is operable by a lever 304 which is biased by a spring 305 in such a direction as to urge the plunger upwardly. To lower the plunger 302 and thereby permit unobstructed movement of the tube 42 to the capping station 67, the lever 304 is provided with an arm 306 adapted to be engaged by a tap-

5

pet rod 308 which is carried by the vertically reciprocating member 165 which operates the bar 162 and the rods 163 and 164. Adjacent the top of the stroke of the member 165, the rod 308 pushes the arm 306 upwardly and thereby retracts the plunger 302 flush with the top plate 194. As the member 165 begins its down stroke, the rod 308 is withdrawn from the arm 306, with the result that the spring 305 raises the plunger 302 and thereby pushes the tube 42 into the recess 300.

10

A supply of the caps 44 is provided at the top capping station 67 by means of a tubular magazine 310 mounted on a plate 312 which is swingable outwardly on a vertical pivot 314 connected to the plate 301, a clamping screw 315 being provided to hold the plate 312 in its normal position. A slicer blade 316 is provided to advance the caps 44 from the magazine 310 to the upper end of the recess 300. The slicer blade 316 is mounted on a vertical shaft 318 operable by an arm 320 on the oscillating indexing sleeve 79. A roller 321 on the outer end of the arm 320 is engageable with an arm 322 mounted on the shaft 318. A spring 324 is provided to bias the arm 322 against the roller 321. Advancing movement of the slicer blade 316 is effected by the spring 324, while return movement of the blade 25 is positively brought about by the arm 320. It will be understood that the cap 44 is advanced into the recess 300 prior to the insertion of the packaging tube 42.

30

The cap 44 is driven into the top of the tube 42 by means of a plunger 326 mounted on the vertically reciprocating bar 162. The plunger 326 is admitted to the upper end of the recess 300 through an aperture 328 in a cover plate 329.

35

After the cap 44 has been driven into the tube 42, the plunger 326 is withdrawn upwardly. Adjacent the top of the stroke of the plunger 326, the tube-lifting plunger 302 is moved downwardly by the tappet rod 308, with the result that the tube 42 moves downwardly out of the recess 300. The conveyor nest 51 then indexes the tube 42 until it is removed from the nest by 40 the fingers 71 and 72.

40

While the operation of the machine will be apparent from the foregoing description, it may be helpful to offer a brief summary. The machine is prepared for operation by loading a supply of tubes 42 into the hopper 47 and by filling the magazines 174 and 310 with caps 44. 45 By means of suitable piping, the ice cream compartment 234 of the hopper 233 may be connected to an ice cream freezer or some other source of fluent material. Likewise, the compartment 235 of the hopper 233 may be connected to a source of fluent material, but it is the more common practice simply to fill the compartment with syrup or other material adapted to form cores in the ice cream packed into the tubes 42.

45

With the machine in operation, the oscillating agitating plate 110 works the tubes downwardly in the hopper 47 so that they enter the ramp 106. The feed lever 126 pushes the tubes one at a time into the erecting chamber 125. During the dwell periods of the conveyor 49, the erecting lever 142 swings the successive tubes 42 into upright position and advances them into the pockets 52 of the conveyor nest 51.

50

By the action of the pawl 77 and the ratchet wheel 76, the nest 51 is advanced step by step. The nest is registered in each successive position by the entry of the locking pin 92 into the apertures 93 in the ratchet wheel 76.

55

After being fed to the nest 51, the tubes are advanced to the testing station 57. At this station, the vertically reciprocating plate 154 is normally arrested in its downward movement by the upper end of the tube 42. If there is no tube in the nest 51, the spring 159 carries the plate 154 downwardly until the plate operates the switch 172 and thereby stops the machine so that a tube may be inserted manually. This arrangement prevents the spillage of fluent material into an empty conveyor

70

75

pocket. The tubes are next advanced to the capping station 60. After the slicer blade 182 has advanced a cap 44 into the lower end of the recess 195, the vertically reciprocating plunger 197 pushes the tube 42 downwardly into the recess. The plunger 202 then drives the cap 44 into the lower end of the tube 42 and moves the tube out of the recess 195 as the plunger 197 is withdrawn upwardly.

At the testing station 62, the plunger 211 moves upwardly into the tube 42 to determine whether a cap is present in the tube. If there is no cap in the tube, the spring 221 carries the plunger 211 upwardly until the plunger-operating lever 214 operates the switch 225 and thereby stops the machine so as to prevent spillage of fluent material from a bottomless tube. If a cap is present in the tube, it arrests the plunger 211 before the switch 225 can be operated. The hold-down arm 226 prevents the plunger 211 from raising the tube 42 at the testing station 62.

Next, each tube 42 is advanced to the filling station 66. The finger 272 carried by the vertically reciprocating rod 260 moves the tube 42 upwardly into telescopic relation with the outer filling nozzle 230. With the tube 42 raised, fluent materials are extruded into the tube through the outer and inner nozzles 230 and 231. As the filling progresses, the stripper plate 276 pushes the tube downwardly off the nozzle 230 until the lower end of the tube is arrested by the flipper blade 290. This blade 290 moves under the tube during its upward movement after being deflected by the side wall of the tube as the tube is indexed to the filling station. The flipper blade 290 arrests the tube 42 with its upper end even with the lower end of the nozzle 230. Thus the tube 42 shears off the fluent material as the conveyor nest 51 indexes the tube to its next position. After passing the flipper blade 290, the tube is pushed downwardly by the paddle 298 on the vertically reciprocating bar 162.

At the top capping station 68, the slicer blade 316 advances a cap 44 into the upper end of the recess 300. Each tube 42 is pushed upwardly into the recess 300 by the plunger 302. The plunger 326 on the vertically reciprocating bar 162 then drives the cap into the upper end of the tube.

From the top capping station, the tubes are carried in the nest 51 until they are cammed outwardly by the stripper fingers 71 and 72, whereupon the tubes fall onto the apron 73 from which they may be removed for packaging and shipment.

It will be apparent that the operation of the packaging machine is fully automatic. The machine may be kept in continuous operation simply by maintaining the supplies of packaging tubes, caps, and fluent material. Spillage of the fluent material is prevented by the provision of the testing devices at the two testing stations. It will be understood that the machine will package various fluent materials, such as jams, jellies, syrups, or loose granular dry materials, for example, in addition to ice cream.

Various modifications, equivalents, and alternative constructions may be employed without departing from the true spirit and scope of the invention as disclosed in the foregoing description and the accompanying drawings, and as defined in the following claims.

I claim:

1. An ice cream packaging machine, comprising a magazine for holding a supply of tubular containers, a rotatable conveyor wheel having a plurality of peripherally spaced recesses for receiving the tubular containers, a feeding mechanism for feeding the containers from the magazine to the conveyor wheel, means for indexing said conveyor wheel to advance the containers to a plurality of stations therearound, means at one of said stations for inserting a disk-shaped cap into the lower end of each of the tubular containers, means at a succeeding station for stopping said machine in response to the

absence of a cap in the container at said succeeding station, filling means at another succeeding station including a downwardly extending tubular nozzle, means for raising each of the containers and thereby telescoping the container over said nozzle, means for extruding ice cream from said nozzle into the container, means for lowering the container as it is filled with ice cream, means for arresting downward movement of the container with the upper end thereof at substantially the level of the lower end of said nozzle, the upper end of the container thereby shearing off the ice cream at the lower end of said nozzle when the conveyor wheel is next indexed, means at still another succeeding station for inserting a disk-shaped cap into the upper end of the container, and means at still another succeeding station for removing the tubular container from said conveyor wheel.

2. A machine for packaging fluent material, comprising a magazine for holding a supply of container tubes, a conveyor having a plurality of pockets for receiving the tubular containers, a feeding mechanism for feeding the tubes from the magazine to said conveyor, means for indexing said conveyor to advance the containers to a plurality of stations, means at one of said stations for inserting a disk-shaped cap into the lower end of each of the tubes, means at a succeeding station for stopping said machine in response to the absence of a cap in the lower end of the tube at said succeeding station, filling means at another succeeding station for extruding fluent material into the tubes, means at another succeeding station for inserting a disk-shaped cap into the upper end of each of the tubes, and means at still another succeeding station for removing the tubes from said conveyor.

3. A machine for packaging ice cream or the like, comprising a conveyor having a plurality of pockets for receiving tubular containers, a feeding mechanism for feeding containers to the conveyor, means for indexing said conveyor to advance the containers to a plurality of stations, means at one of said stations for capping the lower end of each of the tubular containers, filling means at another succeeding station including a downwardly extending tubular nozzle, means for raising each of the containers from an initial level and thereby telescoping the container over said nozzle, means for extruding ice cream from said nozzle into the container, means for engaging and positively moving the container downwardly as it is filled with ice cream, means for arresting downward movement of the container substantially above said initial level and with the upper end thereof at substantially the level of the lower end of said nozzle, the upper end of the container thereby shearing off the ice cream at the lower end of said nozzle when the conveyor wheel is next indexed, means at another succeeding station for capping the upper end of the container, and means at still another succeeding station for removing the tubular container from said conveyor.

4. In an ice cream packaging machine, the combination comprising a rotatable conveyor element for receiving and advancing packaging tubes, means for cyclically indexing said conveyor element to advance the tubes to a plurality of stations, capping means at one of said stations for inserting a disk-shaped cap into each of the tubes, said capping means comprising a member having a recess for receiving one end of the tube, a cyclically operable plunger for telescopically engaging the opposite end of the tube and pushing the tube into said recess, a magazine for receiving a stack of caps, a cyclically operable feeder blade for slicing the lowermost cap from the stack and feeding the cap edgewise into aligned relation with said recess, and a cyclically operable cap driving member for pushing the cap into the tube, said recess positioning the tube in concentric relation to the cap, said plunger retracting after insertion of the cap to withdraw the tube from the recess.

5. In an ice cream packaging machine, a conveyor ele-

ment for receiving and advancing a succession of packaging tubes, means for indexing the conveyor element to advance the tubes to a plurality of stations, means at one of said stations for inserting a generally disk-shaped cap into one end of each tube, and cap-detecting means at a succeeding station for stopping operation of the machine in response to the absence of a cap in the tube, said cap-detecting means comprising a plunger movable into the tube, a cyclically oscillable member having a range of movement sufficient to carry said plunger into the tube beyond the normal position of the cap therein, means forming a lost motion connection between said oscillable member and said plunger to provide for full movement of said oscillable member when said plunger is arrested by a cap in the tube, said lost motion connection including resilient means for carrying said plunger through the full range of movement of said oscillable member in the absence of a cap, said resilient means being effective to yield in the presence of a cap, and a control element operable by full movement of said plunger to stop the operation of the machine.

6. In a packaging machine, a conveyor for receiving and advancing packaging tubes to a plurality of stations, means at one of said stations for capping one end of each tube, and cap-detecting means at a succeeding station for stopping operation of the machine in response to the absence of a cap on the tube, said cap-detecting means comprising a member movable into the tube, yieldable means for cyclically advancing said member, said yieldable means being effective to yield if said member is arrested by a cap on the tube, and a control element operable by full movement of said member to stop the operation of the machine.

7. In a packaging machine, a conveyor having a plurality of pockets for receiving packaging tubes, means for feeding a tube into each of said pockets in succession, means for indexing the conveyor to advance the tubes to a plurality of stations, and tube-detecting means at one station for stopping operation of the machine in response to the absence of a tube in one of said pockets, said tube-detecting means comprising a member movable into said pocket at said one station, yieldable means for cyclically advancing said member, said yieldable means being effective to yield if said member is arrested by a tube in said pocket, and a control element operable by full movement of said member to stop the operation of the machine.

8. In an ice cream packaging machine, the combination comprising a conveyor element for receiving and advancing a plurality of packaging tubes, a tubular generally vertical filling nozzle overlying a station along said conveyor element, said conveyor element being effective to carry the tubes successively to said station, a cyclically reciprocable lifter for raising each of said tubes at said station and thereby moving the tube over said nozzle into telescopic relation therewith, means for extruding ice cream or the like from said nozzle into the tube, a stripper element movable with said lifter for engaging the upper end of the tube and pushing the tube downwardly off the nozzle as the tube is being filled, a flipper blade biased toward said station, said flipper blade being deflected

by the tube when indexed to said station and being effective to move under the tube during upward movement thereof so as to arrest downward movement thereof with the upper end of the tube at the level of the lower end of said nozzle, the upper end of the tube thereby being effective to shear off the ice cream even with the lower end of said nozzle when the tube is advanced away from said station by the conveyor element.

9. In a machine for packaging fluent material, the combination comprising a conveyor for receiving and advancing a plurality of packaging tubes, a tubular generally vertical filling nozzle at a point along said conveyor, means for effecting relative movement between said nozzle and the tube at said point and thereby moving said nozzle and the tube into telescopic relation, means for extruding fluent material from said nozzle into the tube, a stripper element for pushing the tube off the nozzle as the tube is being filled, and means for arresting said tube with one end thereof even with the end of said nozzle to shear off the fluent material when the tube is advanced away from said point by said conveyor.

10. In a machine for packaging fluent material, the combination comprising a conveyor for receiving and advancing a plurality of packaging tubes, a tubular generally vertical filling nozzle at a point along said conveyor, said conveyor being effective to carry the tubes successively to said point, a cyclically reciprocable lifter for raising each of said tubes at said point and thereby moving the tube over said nozzle into telescopic relation therewith, means for extruding fluent material from said nozzle into the tube, means for pushing the tube downwardly off the nozzle as the tube is being filled, an arm biased toward said point for deflection by the tube, said arm moving under the tube during upward movement thereof and thereby arresting downward movement thereof with the upper end of the tube at the level of the lower end of said nozzle, the upper end of the tube thereby being effective to shear off the fluent material even with the lower end of said nozzle when the tube is advanced away from said point by said conveyor.
